Primary Examiner — Rhea Shields(74) *Attorney, Agent, or Firm* — Timothy G. Ackermann(57) **CLAIM**

The ornamental design for a multi-socket electrical outlet, as shown and described.

DESCRIPTION

FIG. 1 is a perspective view of a multi-socket electrical outlet showing a first embodiment of the present invention;

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof.

FIG. 8 is a perspective view of a multi-socket electrical outlet showing a second embodiment of the present invention;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof; and,

FIG. 15 is a top view shown in an environment.

In the drawings, the broken lines are for the purpose of illustrating environment only and form no part of the claimed design. The dash-dot-dash broken lines define the boundaries of the claim and form no part of the claimed design.
